JAMES SPEAR, OF PHILADELPHIA, PENNSYLVANIA.

Letters Patent No. 84,312, dated November 24, 1868.

IMPROVEMENT IN RAILROAD-CAR STOVES.

The Schedule referred to in these Letters Patent and making part of the same.

To all whom it may concern:

Be it known that I, JAMES SPEAR, of the city and county of Philadelphia, and State of Pennsylvania, have invented an Improvement in Railway-Car Stoves; and I do declare that the following is a clear and exact description thereof, reference being had to the accompanying drawings, and letters of reference marked thereon.

The nature of my invention consists in the arrangement of self-acting valves, on the top plate of a railroad-car stove, in such a manner as to allow the stove-pipe to extend through the pipe which conveys cold air to the stove, and by which means the air is not only heated already when passing down around the stove-pipe, but the necessity of making a separate hole for each of the pipes is obviated, and a great saving in room—a very important item in a railroad-car—effected.

Figure 1 is a sectional view of the stove, with the valves open.

Figure 2 is a view of the two valves, showing the weights, B B, on the under side.

Figure 3 is a view of the top plate, with the valves A A in it partly open.

Figure 4 is a view of the ring between the valves, with arms and bearings on which the journals of the valves work, and which is fastened to the top plate, allowing the stove-pipe to pass through it between the valves.

The fire-box of the stove is surrounded by an air-jacket, to the centre of the top of which the cold-air pipe is attached. The ring, fig. 4, with its journal, is attached to the top plate of the air-jacket, where it joins the cold-air pipe, and to its journals are attached the valves A A, in such a manner that, by their weighted arms B, they are held, when in a normal position, against the top plate, so as to close the cold-air pipe. The stove-pipe extends from the top of the fire-box through the ring, fig. 4, and the cold-air pipe, out over the roof of the car.

When the car is in motion, the cold air rushing down the cold-air pipe, forces the valves A A down, and the

downward current of air getting heated from the moment it enters the vertical part of the cold-air pipe, by reason of the stove-pipe passing through the latter, till it has passed the fire-box, is distributed into the car through openings in the lower part of the hot-air jacket. When the cars stop, the downward current of cold air ceases, the valves A A close by their weights B B, and the hot air is thus prevented from escaping.

By my improved arrangement of the valves, three great advantages over any other construction or arrangement are effected:

First, the cold air begins to be heated the moment it enters the vertical part of the cold-air pipe, as it surrounds the hot stove-pipe, and thus a car is much quicker heated, the air passing out of the jacket into the car being much hotter than if the stove-pipe passed out of the car alongside of the cold-air pipe.

Secondly, the necessity of cutting a separate hole in the roof of a car for each of the pipes is avoided. Car-roofs are made very light, of necessity, to avoid too great weight, and any openings in the same tend to weaken them. By passing both pipes, one within the other, through one hole only, I thus gain in the strength of the roof; and,

Thirdly, I effect a saving in room in the car, which, especially in passenger-cars, is of great importance, as is well understood.

I am well aware that self-acting valves have been used in cold-air pipes in railroad-car stoves, and those I do not claim broadly; but

What I claim as new, and desire to secure by Letters Patent, is—

The arrangement of the valves A A on the top plate of the stove, in such a manner as to allow the stove-pipe to extend through the cold-air pipe, substantially as and for the purposes set forth.

JAMES SPEAR.
